UNITED STATES PATENT OFFICE.

JOSEPH GEORGE RUSSELL, OF HOBOKEN, NEW JERSEY.

SAFETY DEVICE FOR ELEVATORS.

Application filed April 26, 1927. Serial No. 186,713.

This invention relates to new and useful improvements in elevator safety devices and aims to provide a relatively novel, simple and useful mechanism for association with elevators and their guide shafts, so as to facilitate the mechanical stoppage of the elevator should the same drop within the shaft, due to the breakage of the elevating and lowering cables or the slippage of the same upon their operating pulleys.

An important object of the invention is to provide a safety device of this character, that may be installed within conventional elevators and their guide shafts without requiring any change in the structure of the elevator or shaft, and without interfering with the elevator mechanism.

With the foregoing and other objects in view the invention consists in the novel formation and arrangement of parts as will be hereinafter described.

In the drawings, wherein for the purpose of illustration is shown the preferred embodiment of my invention:

Figure 1 is a fragmentary vertical section through an elevator and its guide shaft with a safety device equipment in accordance with the present invention.

Figure 2 is a detail horizontal section, taken substantially on the line 2-2 of Figure 1, and looking downwardly in the direction of the arrows.

Figure 3 is a fragmentary horizontal section taken substantially on the line 3-3 of Figure 1, but disclosing the means for securing the safety device operating lever in applied position.

Figure 4 is an enlarged view disclosing the upper end of one of the brake beams in elevation, and its particular brake shoe in longitudinal cross section, and

Figure 5 is an outside elevation of one of the brake beams per se.

Now having particular reference to the drawings, 5 designates generally a conventional elevator movable vertically within the usual shaft.

In carrying out my invention, there is arranged vertically within the shaft at the four corners thereof, vertically extending brake shoe engaging bars, 6, four of these bars being arranged at each corner, and in spaced pairs as clearly disclosed in Figure 2. Arranged upon the under side of the flooring of the elevator 5 at opposite sides thereof are spaced parallel frame boards 7-7,

connected by a predetermined number of spaced cross members 8. Arranged between two of these cross members at the front side of the elevator 5, are spaced parallel straps 9-9, through which, as well as the frame boards 7-7 are arranged the opposite ends of the rocker shaft 10. Connected to this shaft 10 between the straps 9-9 of the frame boards 7-7 at the operator's side of the elevator 5 is the lower end of a relatively elongated throw lever 11, that extends upwardly through a slot 12' in the elevator flooring as clearly disclosed in Figure 1. Connected to this lever 11 above and below the rocker shaft 10 are forwardly and rearwardly extending links 12 and 13, the lower link being pivotally connected at its inner end to a rearwardly extending bar 14, guided through large openings in the cross members 8 between the frame boards 7-7 at that particular side of the elevator. The forward link 12 is pivotally connected at its free end to a short sectional bar 15, that projects forwardly of the elevator as clearly indicated in Figures 1 and 2.

Connected to the rock shaft 10 at the opposite side of the elevator is a rocker arm 17, the upper and lower ends of which are pivotally secured to links identical to the links 12 and 13 just described and therefore these links will also be designated by the same reference characters and pivoted to the outer ends thereof are bars similar to the bars 14 and 15 just described, at the opposite side of the elevator and therefore said bars will also be designated 14 and 15, as in Figure 1.

The safety device further consists of four identically constructed brace beams for pivotal attachment to the outer ends of the four bars 14 and 15 at opposite sides of the elevator shaft. Insomuch as the construction of each brace beam together with its associated mechanism is identical in construction, a description of one will suffice for all. Each brace beam is designated 18, and the same is pivoted at its lower end to the outer ends of the bars 14 and 15, while the same extend upwardly between the four bars 6, at the corners of the elevator shaft. Each beam 18 is pivoted, at its center to a horizontal arm 19 extending outwardly from the adjacent side wall of the elevator 5, so as to permit the same to be rocked thereon. The upper end of each beam 18 is formed at its inner edge with an arcuate slot 20,

while pivoted to each beam as at 21 is the inner bifurcated end 22 of a brake head 23, that extends outwardly from the elevator as clearly disclosed in Figure 1. The forward 5 end of each head is provided with a plate, while attached thereto is a facing of braking material 24. Extending through the bifurcated end 22 of each brake head 23 as well as the arcuate shaped slot 20 of its particular beam 18 is a guide pin 25, the particular connection between each head and beam allowing the head to pivot thereon so that the same may engage in a flush manner with the outermost bars 6, at each corner 15 of the elevator shaft.

Connected to the ends of the rocker shaft operated bars 14 and 15 between the innermost bars 6 at the four corners of the shaft and the lower end of the brake beams 18 are brake shoes 26, each of which is provided at its inner face with a strip of braking material 27 for engaging the innermost bars 6 at the corners of the elevator shaft.

Obviously when the lever 11 is in the position disclosed in Figure 1, the various brake beams 18 are so swung upon their pivots as to cause the brake members at the upper and lower ends thereof to engage the inner and outer pairs of bars 6 at the corners 25 of the elevator shaft, so as to prevent the movement of the elevator or to permit the same to slowly descend.

Within the elevator 5 is a horizontally arranged segmental arm 28, formed throughout substantially its entire length with a slot 29, one edge of which is formed with ratchet teeth 30 and through which slot projects the lever 11, this construction being provided, in order that the lever may be 35 ratcheted over the teeth 30 and caught back of any predetermined run thereof, so that the same may be latched in operative position. In order that a further pull upon the lever 11 may be occasioned after being drawn 40 backwardly as far as possible by the operator pulling directly thereon there is provided a turn buckle arrangement 31 consisting of a pair of rods 32—32 connected at their inner ends by a hand wheel turn buckle 33, the innermost rod 32 being pivoted to the side of the elevator and the opposite end thereof being provided with a suitable hook 34 for engagement over the lever 11, as indicated in Figure 3. Obviously, when this 45 turn buckle arrangement is engaged at its free end with the lever 11 and the hand wheel 33 turned in the proper direction, the lever 11 will be further drawn rearwardly so as to cause the engagement of the brake 50 shoes with the pairs of bars 6, to absolutely prevent any dropping of the elevator. It will thus be seen that I have provided a highly novel, simple and efficient safety device for elevators that is well adapted for

all of the purposes heretofore designated, even though I have herein shown and described the invention as consisting of certain detail elements, it is nevertheless to be understood that some changes may be made therein without departing from the spirit of the invention or the scope of the appended claims.

Having thus described my invention, what is claimed is:

1. In a safety stop for elevators, spaced vertically extending brake bars at the corners of the elevator shaft, a pair of units suspended from the floor of the elevator cage, each unit being arranged between the brake bars at opposed corners of the shaft, each unit including a forwardly and rearwardly extending bar, a brake beam pivoted to the outer end of each bar and arranged between the spaced brake bars at that particular corner of the shaft, a pivotal connection between each beam and the elevator cage, brake shoes at the ends of each beam for engagement with the opposed faces of the spaced brake bars and means common to the bars of each unit extending into the cage whereby the said beam bars may be operated to so swing the shoes as to engage the brake shoes with said brake bars.

2. In a safety stop for elevators, spaced vertically extending brake bars at the corners of the elevator shaft, a pair of units suspended from the floor of the elevator cage, each unit including brake beams at the opposite ends thereof arranged between the spaced brake bars at two aligned corners of the shaft, brake shoes upon the ends of the beams, and single means within the elevator cage, whereby all of the beams may be so swung as to cause the engagement of the shoes with the opposed faces of said spaced brake bars.

3. In a safety stop for elevators, spaced vertically extending brake bars at the corners of the elevator shaft, a pair of units suspended from the floor of the elevator cage, each unit being arranged between the brake bars at opposed corners of the shaft, each unit including forwardly and rearwardly extending bars, a brake beam pivoted to the outer end of each bar and arranged between the spaced brake bars at their corner of the shaft, a pivotal connection between each beam and the elevator cage, a pivotal brake shoe at the upper end of each brake beam for engaging certain of the brake bars at the respective corners of the elevator shaft, and means common to said beam bars and extending into the elevator cage, whereby the beam bars may be operated to so swing the beams as to engage the brake shoes with said brake bars.

In testimony whereof I affix my signature.
JOSEPH GEORGE RUSSELL.
